UNITED STATES PATENT OFFICE.

EDWARD L. FELKER, OF TOLEDO, OHIO.

DESIGN FOR A SUSPENDER ATTACHMENT.

SPECIFICATION forming part of Design No. 35,135, dated October 1, 1901.

Application filed September 3, 1901. Serial No. 74,261. Term of patent 3½ years.

To all whom it may concern:

Be it known that I, EDWARD L. FELKER, a citizen of the United States, residing at Toledo, in the county of Lucas and State of Ohio, have invented and produced a certain new and original Design for Suspender Attachments; and I do declare the following to be a full, clear, and exact description of the invention, such as will enable others skilled in the art to which it appertains to make and use the same.

The invention relates to a new and original design for a suspender attachment; and it consists of the design shown in the accompanying drawings, in which—

Figure 1 is a front view, and Fig. 2 is an edge or side view.

The leading feature of the design consists of a ring-shaped body *a*, terminating at one point in its circumference in a loop *b*, lying in the same plane and terminating at a point diametrically opposite the loop in a shank *c*, projecting at right angles to the plane of the loop and provided with a head *d*.

What I claim is—

The design for a suspender attachment, as herein shown and described.

In testimony whereof I have hereunto set my hand in presence of two subscribing witnesses.

EDWARD L. FELKER.

Witnesses:

JNO. W. ENRIGHT,
WM. A. MILLS.
